(57) **CLAIM**

The new, original and ornamental design for a faucet, as shown in the drawings and described herein.

DESCRIPTION

FIG. 1 is a perspective rear view, from the top, right side of a faucet, showing the design thereof;

FIG. 2 is a perspective side view, from the front, left side of the faucet;

FIG. 3 is a top plan view of the faucet in a first position thereof;

FIG. 4 is a top plan view of the faucet in a second position thereof

FIG. 5 is a front elevational view of the faucet;

FIG. 6 is a side elevational view, from the left side of the faucet;

FIG. 7 is a side elevational view, from the right side of the faucet; and,

FIG. 8 is a perspective view to the right, from the bottom of the faucet.

The broken lines are included for the purpose of illustrating portions of the faucet that forms no part of the claimed design.
